(57) **CLAIM**

The ornamental design for a glass bottle water pipe, as shown and described.

DESCRIPTION

FIG. 1 shows a perspective view of a glass bottle water pipe; FIG. 2 shows a front view of the glass bottle water pipe; FIG. 3 shows a rear view of the glass bottle water pipe; FIG. 4 shows a right side view of the glass bottle water pipe; FIG. 5 shows a left side view of the glass bottle water pipe; FIG. 6 shows a top plan view of the glass bottle water pipe; and, FIG. 7 shows a bottom plan view of the glass bottle water pipe.

The glass bottle water pipe is shown with a symbolic break in its length. The appearance of any portion of the article between the break lines forms no part of the claimed design. The broken lines shown in FIG. 7 depict portions of the glass bottle water pipe that form no part thereof.
